UNITED STATES PATENT OFFICE.

WILLIAM GRUS, JR., OF CHICAGO, ILLINOIS.

ADJUSTABLE OILER.

Application filed April 1, 1922. Serial No. 548,576.

To all whom it may concern:

Be it known that I, WILLIAM GRUS, Jr., a citizen of the United States, residing at Chicago, in the county of Cook and State 5 of Illinois, have invented certain new and useful Improvements in an Adjustable Oiler, of which the following is a specification.

This invention relates to the lubrication of leaf springs for automobiles and other 10 vehicles, and more particularly to an adjustable oiler for springs of this class which can be varied for springs of different widths and thicknesses. The principal object of the invention is therefore to provide an im- 15 proved adjustable oiler of this kind so that when it is once set for a certain width of spring, it will remain in that position until adjusted for a different width.

In the accompanying drawings, Fig. 1 20 is a top plan of an oiler constructed in accordance with the principles of this invention; Fig. 2 is a section taken on the line 2-2 of Fig. 1; Fig. 3 is a side elevation of the oiler as applied to a leaf spring; Fig. 4 25 is a section taken on the line 4-4 of Fig. 3; and Fig. 5 is a detail of one of the oiler sides.

It is desirable to provide an adjustable oiler to accommodate various sized springs, 30 and in order to make such an oiler fit properly over the tops of the springs, the sides should set snugly against the edges thereof. The present invention provides a screw adjustment for the sections of the top which 35 may be varied as closely as desired within the limits of its adjustment.

Referring more particularly to the drawings, the oiler comprises a pair of angular casing sections 4 and 5 which are adapted 40 to fit over the upper opposite edges of a leaf spring and to overlap an amount sufficient to provide for a considerable adjustment of these two casing parts to accommodate leaf springs of various widths. One of the cas- 45 ing parts 5 has a raised boss 6 to which an oil cup 7 is attached. The oil cup has a spring pressed lid 8 which is opened against the spring pressure to insert oil within the casing. The overlapping casing member 5 50 is formed with bent edges 9 adapted to engage under the edges of the other casing member 4 thereby providing a guide in which it is slidable.

Both of the casing members 4 and 5 are 55 formed at their upper corners with strengthening bosses 10 and at their inner depend-

ing edges with teeth 11. The lowermost tooth 12 at each edge is somewhat longer than the others and is inclined and rounded inwardly. At the lowermost end of each 60 casing part is an adjustable extension 13 having inwardly bent edges 14 except at the top where it is provided with lateral projections 15 adapted to engage between 65 the teeth 11. The lowermost teeth 12 of 70 the casings 4 and 5 are bent outwardly and inclined so that these extensions 13 may be first inclined outwardly to free the projections 15 from engagement with the teeth and then adjusted as desired, without ac- 75 tually disengaging the extensions 13 from the casing parts.

In order to adjust the casings 4 and 5 for different spring widths, an internally threaded shell 16 is attached to the upper 75 portion of one of the casing parts, and a screw 17 is inserted from the outside through the opposite portion of the other casing part. It is obvious that the movement of the screw in the shell will force 80 the casing parts together and will allow them to be extended only as far as permitted by the screw adjustment, and that when once adjusted for any predetermined width, 85 no further adjustment is necessary for keeping the oiler in this position. Furthermore, this screw connection holds the casing parts together against loss or displacement before the oiler is applied to a 90 spring.

Within the casing parts thus assembled, a continuous pad of felt or other fibrous absorbent material is inserted, of sufficient 95 length to extend over the top and against the edges on both sides of a spring to which the oiler is applied and with holes or cutouts at the ends through which fastening bolts for the casing members are inserted. If desired, there may be a cut out portion 19 100 at the top and center of the pad which provides a space for the sleeve 16 and bolt 17 and a channel for lubricant to the side portions of the oiler and from the oil cup 7. A spacer 20 may be inserted in this cutout portion 19 on top of a leaf spring, and it is preferably U-shaped in cross section fitting the cutout 19 with extensions 21 below the adjacent extremity of the casing section 4.

To connect the extensions 13 of the casing 110 parts below the leaf spring, a bolt 22 is inserted through perforations 23 in the casing

extensions after they are adjusted to bring the bolt up tight against the bottom of the leaf spring, and a nut 24 is drawn up tight. The spring action of the extensions 13 and 5 the sides of the casing section 4 will hold the oiler in place without danger of dislodgment.

In applying the oiler to a spring the adjustment of the casing sections 4 and 5 may 10 be made before or after the oiler is applied to the spring by simply tightening the screw 17 in the sleeve 16. The side extensions 13 are preferably adjusted for the spring thickness before the oiler is applied to the 15 spring by engaging the projections 15 with the proper teeth 11. Another object of the screw adjustment is that the pads 18 can be tightened against the edges of the spring after the oiler has been in use for some time 20 thereby preventing leakage of oil from the sides of the oiler.

I claim:

1. In a leaf spring oiler, telescoping casing sections adapted to fit over the edge of a spring, and means within the sections extending over the top of the oiler for drawing the sections together against the edges of a spring.
2. In a leaf spring oiler, casing sections 30 slideable one within the other and fitting over the top of a spring, and fastening means engaging the outer sides of the casing parts adapted to draw them together over the top and against the edges of a spring.
3. In a leaf spring oiler, telescoping casing parts fitting over the top and against the edges of a spring, and means including a threaded shell secured to one of the casing parts, and a screw extending through the 40 other casing part into the threaded shell for drawing the parts together.
4. In a leaf spring lubricator, a pair of casing parts overlapping over the top of a spring and extending downward partially

over the opposite edges thereof, means for 45 drawing the casing parts together over the top of a spring, and adjustable extensions at the bottom of each casing part.

5. In a leaf spring lubricator, a pair of casing parts overlapping over the top of a 50 spring and extending downward partially over the opposite edges thereof, means for drawing the casing parts together over the top of the spring, adjustable extensions at the bottom of each casing part, and fastening means engaging the extensions below the spring and connecting them together.

6. In a leaf spring oiler, the combination with a casing fitting over the top and downwardly at the sides of a leaf spring, of means 60 for admitting lubricant at the top of the casing, a pad for confining the lubricant against the edges of the leaves, said pad extending over the top of a spring and having a cutout portion at the center thereof, and a 65 spacer fitting in the cutout portion to prevent the sides of the cutout portion of the pad from collapsing.

7. In a leaf spring oiler, a pad fitting over the top and downwardly against the sides 70 of a leaf spring and having a cutout portion in the center extending over the top of a spring to which it is applied, and spacing means fitting in the cutout portion to prevent the adjacent sides of the pad from being displaced.

8. In a leaf spring oiler, a sectional casing adjustable over the top of a leaf spring, a pad insertable therein and fitting over the top of a spring in the casing, the pad being 80 formed with a cutout to provide a passage at the top of a spring, means for drawing the sections together, and means within the casing fitting in the cutout portion of the pad to prevent the sides thereof from filling up 85 the passage formed by the cutout when the casing sections are drawn together.

WILLIAM GRUS, JR.
